UNITED STATES PATENT OFFICE.

JOHN W. LANHAM, OF DANVILLE, ILLINOIS.

WRENCH.

No. 820,651.

Specification of Letters Patent.

Patented May 15, 1906.

Application filed December 27, 1904. Serial No. 238,457.

To all whom it may concern:

Be it known that I, JOHN W. LANHAM, a citizen of the United States, residing at Danville, in the county of Vermilion and State of Illinois, have invented certain new and useful Improvements in Wrenches, of which the following is a specification.

My invention relates to wrenches, and especially to that class of wrenches provided with means for varying the size of the work-receiving opening.

The object of my invention is to provide a wrench which may be cheaply manufactured and which will exert upon the work a high degree of clamping pressure.

A further object of my invention is to provide a wrench having a traveling outer jaw, with means for securing the said jaw at a desired adjustment relatively to the handle and to permit an angular movement of the jaw when so adjusted.

With these and other objects in view the present invention consists in the combination and arrangement of parts, as will be hereinafter more fully described, shown in the accompanying drawings, and particularly pointed out in the appended claim, it being understood that changes in the form, proportion, size, and minor details may be made within the scope of the claim without departing from the spirit or sacrificing any of the advantages of the invention.

In the drawings, Figure 1 is a view in side elevation of my improved wrench. Fig. 2 is a side view of my wrench in vertical section. Fig. 3 is a perspective view of the yoke member of my improved wrench. Fig. 4 is a perspective view of the pawl, operating-lever, and spring of my wrench.

Like characters of reference designate corresponding parts throughout the several views.

In its preferred embodiment my improved wrench consists of a rigid handle member 1, conveniently formed and proportioned to be grasped by the operator and provided at its inner end with a work-engaging face 2. In practice it is found convenient to form the work-engaging face 2 integral with a block 3, set into a groove in the end of the handle member 1 and secured therein by a rivet or screw 4. The handle member 1 is also provided with upstanding guides 5 upon each side thereof and preferably formed integral

therewith and between which is formed an opening 6 in the handle member 1.

A yoke 7 is mounted upon and embraces the handle member 1 and is pivotally secured thereon by a screw or rivet 8, passing through holes 9. The yoke 7 is so proportioned and disposed that an angular movement thereof causes the said yoke to abut against the guides 5, and the movement thereof is thereby limited. A jaw member 10 is mounted within the yoke 7 and provided at its upper edge with teeth 11. The jaw member 10 is also provided with a work-engaging face 12, disposed opposite and adapted to operate in conjunction with the work-engaging face 2. A lever 13 is pivoted within the yoke 7 by rivet 14 and has pivotally secured thereto a pawl 15, provided with teeth 16, adapted to engage with the teeth 11 of the jaw member 10 and to hold the said jaw member at any desired adjustment relatively to the yoke 7. A spring 17 is provided, adapted to cause the pawl 15 to automatically engage with the jaw member 10. Within the hole 6 is disposed a spring-pressed bearing-plug 18, adapted to bear against an outwardly-extending leaf 19 of the yoke 7.

The operation of my improved wrench is as follows: With the parts assembled, as shown in Fig. 1, the jaw 10 may be given a desired adjustment by a pressure upon lever 13, raising the teeth 16 of the pawl 15 out of engagement with the teeth 11 and permitting a sliding movement of the jaw member outwardly. Pressure upon the lever 13 also presses the yoke 7 out of engagement with upstanding guides 5, thereby opening the work-engaging jaws of the wrench to the maximum extent for a given adjustment. When the desired adjustment is attained, the lever 13 being released, the pawl 15 is automatically caused to engage with the teeth 11 by the spring 17. The jaw may be moved inwardly without depressing the lever 13, as the sloping sides of the teeth 16 will ride up the sloping sides of the teeth 11 against the pressure of the spring 17. The desired adjustment having been attained and the jaw member locked in position, the work is engaged between the work-engaging faces 2 and 12 and the said work grasped firmly therein by the pressure of the spring-pressed plug 18, bearing against the leaf 19 of the yoke. It is obvious that a working pressure exerted

upon the handle member 1 in the direction indicated by the arrow will cause a still greater angular displacement of the yoke 7 and jaw member 10 and a still greater pressure upon the work.

It is obvious that plane work-engaging faces may be substituted for the serrated faces 2 and 12 and that other minor changes may be made without departing from the spirit of my invention.

Having thus described my invention, what I claim as novel, and desire to secure by Letters Patent, is—

The combination in a wrench of a handle member and a jaw at its end, a yoke pivoted

on said member provided with a transverse plate, a spring-pressed pawl between said plate and the handle member; a second jaw located in the yoke and provided with teeth at its outer side, a spring-pressed lever pivoted in the yoke, a pivoted pawl on said lever to engage said teeth, and guiding-lugs for the second member, formed on the handle member.

In testimony whereof I affix my signature in presence of two witnesses.

JOHN W. LANHAM.
